TOOL OPERATING ATTACHMENT FOR PLANERS OR SHAPERS

Filed Sept. 16, 1922

2 Sheets-Sheet 2

UNITED STATES PATENT OFFICE.

HARRY W. WATSON, OF MEMPHIS, TENNESSEE.

TOOL-OPERATING ATTACHMENT FOR PLANERS OR SHAPERS.

Application filed September 16, 1922. Serial No. 588,620.

To all whom it may concern:

Be it known that I, HARRY W. WATSON, a citizen of the United States, residing at Memphis, in the county of Shelby and State of Tennessee, have invented certain new and useful Improvements in a Tool-Operating Attachment for Planers or Shapers; and I do hereby declare the following to be a full, clear, and exact description of the invention, such as will enable others skilled in the art to which it appertains to make and use the same.

This invention relates to an attachment for planing or shaping machines.

It is aimed to provide an attachment whereby the tool will efficiently operate in a curved or inclined path with respect to the axis of the carriage so that the machine will have greater range of use and will particularly enable it to accomplish certain work now done by hand files, for instance the machining of the vanes of pump runners, to afford greater efficiency and accuracy in the performance of such work, save labor and enable more efficient operation of the pump itself. It is to be understood of course that a limitation to this particular work is not to be implied.

Another object is to provide a construction which is attachable to the head of a shaper or planer and adapted for vertical reciprocation to correspondingly move the tool and which movement occurs through the reciprocation of the carriage of the machine in cooperation with a cam means on the frame or table of the machine.

Additional objects and advantages will become apparent from a consideration of the description following taken in connection with accompanying drawings illustrating one practical embodiment.

In said drawings:—

Figure 1 is a side elevation illustrating the attachment placed on a planer or shaper, the latter being shown fragmentarily;

Figure 2 is an enlarged perspective view of the attachment alone;

Figure 3 is a cross sectional view on the line 3—3 of Figure 1;

Figure 4 is a cross sectional view on the line 4—4 of Figure 1;

Figure 5 is a longitudinal detail cross sectional view on the line 5—5 of Figure 4;

Figure 6 is a detail perspective view illustrating a modified form of cam and attaching means.

Like reference characters designate like or similar parts in the different views.

A planer or shaper has been conventionally and fragmentarily illustrated in the drawings to facilitate an understanding of my attachment. Such machine comprises a frame or table A upon which the work is supported and secured as usual and by any suitable means and B designates the reciprocatory carriage which moves the tool with respect to the work. This carriage B has a head as usual as at C.

In reducing the invention to practice, a securing block of any suitable shape is provided as at 10 and adapted to have screws as at 11 passed therethrough and engageable with the head C to secure the parts in place.

Vertically reciprocable on the attaching block 10 is a tool-carrying means generally designated 12. This means 12 includes a slider block 13, directly slidable on the block 10 having side flanges 14 overlapped by retaining flanges 15 on the block 10. Slider 13 as well as the entire tool carrying means is suspended by a rod 16 which is slidable through a guide plate 17, preferably arcuate as shown so as to conform to the outer edge of the head C which it engages and which is adapted to be secured in place as through the medium of fastening bolts 18 passing through the guide plates 17 and into the head block C. Rod 16 has a head at 19 and an expansive coil spring 20 surrounds the rod 16 and engages head 19 and the guide plate 17 so as to normally urge elevating movement of the tool carrying means and primarily serve to support the weight of such tool carrying means.

A cross feed block is provided at 21, 95 adapted for horizontal sliding movement through manipulation of a cross feed screw 22 having a crank or handle 23 of appro-

ropriate design thereon. Cross feed block 21 is overlapped by lugs 24 which may be integral with the slider 13 and by dovetailed lugs 25 fitted into the bottom thereof by the provision of slots or cutaway portions as at 26. Block 21 is adapted to carry the tool. The tool is designated 27 being of a shape according to the work it is adapted to perform and removably carried by a holder 28, 10 preferably passing through a slot 29 thereof and secured in place by a binding screw 30 threaded on said holder. Tool holder 28 extends from an apron 31, either removably or rigidly as preferred and which apron is pivoted as usual as at 32 so that it may swing to enable the tool 27 to avoid binding with the work on the return stroke of the carriage. A down feed screw 33 is associated with the cross feed block 21, being provided 20 with a suitable operating crank or handle at 34. Screw 33 is journaled as in a lug 33^a of slider block 13 and is held against sliding movement by nuts or collars 33^b. Said screw 33 is operatively threaded in a lug 33^c of feed block 21.

Depending from the slider 13 is an arm 35. This arm may be attached to the lower end of the slider or to one side thereof or otherwise as preferred. The lower end of 30 arm 35 has a hole therethrough through which a stud 36 is adapted to be passed and which has an abutment flange 37 integral therewith to engage one side of the arm 35 and which is screw threaded so that a nut 38 may be screwed thereon into engagement with the other side of the arm 35 and thus rigidly secure it to the arm. A sleeve or roller 39 is journaled on the other end of the stud 36.

40 A bracket 39^a is adapted to be fastened to the frame A and it is substantially U-shape in cross section so as to provide a groove 40 and upper and lower track rails 41 extending over the groove and being cam 45 shape as shown, for instance inclined, curved regular or irregular or otherwise. This bracket 39^a is secured in place in any suitable manner as by means of fastening plates at 42 through the medium of bolts 43 adapted to enter the frame or table A. Slidably disposed in the groove 40 is a block 44 and said block has an opening which is occupied by the roller 39 and adjacent portion of the stud 36.

55 It will be seen that with the tool 27 in place, and the carriage B reciprocating as usual in machines of this character, tool carrying means 12 will be moved vertically simultaneously with such reciprocation and through the reciprocatory movement, thus elevating the entire tool carrying means, and particularly the tool 27, as the same thus follows a path similar to the curvature of the groove 40 due to the connection of the

arm 35 to the slider 13 and with the block 44 through the medium of the stud 36 and friction reducing roller or sleeve 39. Thus will it be realized that simultaneously with the reciprocatory movement of the tool, it is also moved vertically with respect to the 70 axis of the carriage B so that instead of being capable of operating in the same plane as usual, it is capable of operating on an inclined or a curved surface.

It has proven particularly useful in machining the vanes of pump runners, accomplishing work which is usually done by means of hand files, rendering the work more accurate and capable of accomplishment at a considerable saving in labor.

As merely one practical embodiment has been illustrated and described, it will be understood that various changes in the details may be resorted to provided they fall within the spirit and scope of the invention, 85 for instance and as shown in Figure 6, cam bracket 39^a may be supported on the top of the frame or table A rather than at the side thereof as illustrated in Figures 1 to 5. To this end, the bracket 39^a may be 90 bolted or otherwise fastened as at 45 to an angle iron or bracket 46 which in turn may be fastened on the top of the frame or table A in any suitable manner and for instance by means of screws or bolts 47.

I claim as my invention:

1. In a shaper, a slidable carriage, a tool movable with the carriage, and guide means arranged parallel with the movement of the carriage to move the tool in 100 a direction transversely to the movement of the carriage.
2. In a shaper, a slidable carriage, a tool movable therewith, a track arranged 105 parallel with the movement of the carriage, and means cooperating with said track adapted to move said tool transverse to the path of movement of said carriage.
3. In a shaper, a slidable carriage, a tool, means to mount said tool for sliding movement transversely of the carriage, and means to impart said movement to the tool including an arm extending from said means, and a cam track for said arm, said cam track being arranged parallel with the movement 110 of the carriage.

4. In a shaper, a slidable carriage, a slider, a securing plate for said slider attachable to the carriage, spring means to sustain the weight of the slider, a tool carried by 120 the slider, and means coacting with the slider to impart movement thereto transverse to the path of movement of the carriage.

5. In a shaper, a slidable carriage, a tool, means mounting said tool for movement transversely of the carriage, cam means associated with the latter means to impart the

movement thereto, and resilient means to normally sustain the weight of the latter means.

6. In a shaper, a slidable carriage, a slider movable transversely thereof, a securing plate on said carriage for said slider a guide plate, a rod extending from said slider and through said guide plate, a spring on said rod engaging said guide plate, an

abutment on said rod engaged by said spring, said spring being expansive, an arm extending from said slider, a stud on said arm, a slide block engaged by said stud, a cam means for said slide block, and a tool carried by the slider. 10 15

In testimony whereof I affix my signature.

HARRY W. WATSON.
